Filed Oct. 12, 1961, Ser. No. 144,684
7 Claims. (Cl. 182—93)

This invention relates to ladders for railway cars, and more particularly to a safety ladder employed in conjunction with a shifting structure or lading on said car.

Railway cars having a shifting structure or lading, such as the cushioned multi-level type cars transporting automobiles, present a hazard to the user of ladders mounted on the cars. There may be need for using a railway ladder during the loading or unloading of the car or during service of the car. During service the structure or lading carried by the car may move relative to the underframe, due to coupler impact. If the ladder is attached to the moving structure, the user of the ladder may be injured because of the abrupt movement of the structure or lading. If the ladder is attached to the underframe, the user of the ladder may be injured because he may inadvertently extend his hand or foot into the moving structure or lading.

It is an object of this invention to provide for a railway car, having a shifting structure and lading, with a safety ladder so constructed as to protect the user against injury from the moving structure or lading.

Another object of this invention is to provide a safety ladder that may be used to protect a user of the ladder against any danger that may confront him from the front of the ladder, such as by any moving object, fire or explosion.

These and other objects will be apparent from the description and drawings in which:

FIGURE 1 is a side view of a multi-level railway car and the safety ladder applied thereto in accordance with a preferred embodiment of the invention;

FIGURE 2 is an enlarged view of the safety ladder with an end portion of the railway car, as viewed in FIGURE 1, with parts broken away to better show details;

FIGURE 3 is an end side view of the structure shown in FIGURE 2;

FIGURE 4 is an enlarged fragmentary view partly in section of a detail of the structure as shown in FIGURE 3; and

FIGURE 5 is an enlarged plan view of the structure shown in FIGURE 2 with parts removed to show detail.

Referring now, to the drawings in detail, it will be seen that the railway car C is of a multi-level car type having a shifting or sliding frame structure F which is supported and cushioned on underframe U, which in turn is supported on trucks T. This type of car carries lading, such as automobiles A, on three track sections S which are secured on the frame structure F. Safety ladders L are mounted at each end of the car, fixed to the underframe U and extend upwardly relative thereto. Due to coupler impact, since the frame structure F is cushioned on the underframe U, the frame structure F will move longitudinally in relation to the underframe U and ladder L. The user of the ladder may unavoidably extend his arm or any other part of his body within the moving frame structure F and have the part injured or sheared off by the moving frame. However, the present invention provides a ladder with safety means to protect the user, such as will be hereinafter described. In addition, these safety means may protect the user against moving lading on the railway car or if the ladder is used independently, may protect the user against any hazard that may present itself from the front.

2

As clearly shown in the drawings, the ladder L comprises a pair of frame members such as angled members 10 with horizontal treads 11 vertically spaced and extending from the underframe U to the top of the frame structure F. The treads 11 are supported on the angle members 10 by bolts or other means of fastening. The lower portion of the ladder is secured to the underframe by brackets 12 bolted or otherwise secured to the ladder and to the underframe. The upper and intermediate portions of the ladder are welded or otherwise secured to the inwardly looped ends of a channel-shaped rider 14. In turn the rider 14 is slidably received in a U-shaped bracket 15 which is welded or otherwise secured to a vertical stringer 16 of the frame structure S through a cross-plate 17 and bracket 18, as best seen in FIGURES 4 and 5. It should be noted that the upper rider 14 may be slidably received in the upper U-shaped bracket 15 which is secured by welding directly to the frame structure F.

From the preceding, it will be seen that the movement 20 of the frame due to impact will not effect or move the relatively stationary ladder. That is, the frame will move in relation to the ladder. Therefore, to protect the user from extending his hands and feet into the moving frame a guard plate 19 is provided. The guard plate is interposed between the treads 11 and the frame F. The guard plate which includes perpendicular sides 20 is welded or otherwise secured to the ladder's vertical angle members 10, as best shown in FIGURE 5. The extending sides 20 of the guard plate spaces the plate from the treads 11 to permit the user of the ladder to hold the treads and to partially insert his feet within the ladder to ascend or descend the ladder. It is apparent, therefore, that the guard plate 19 protects the user of the ladder from injury by preventing the user from extending his hand or foot or arm or any other part of his body into the moving frame or into any moving lading that may be carried by the frame.

The body of the car, as shown in the drawings, also, supports a lower step 21 and a sidestep 22 secured to the underframe U. The guard plate at this portion of the car is not necessary since there is no relative movement between these steps and the car structure. The improved ladder structure may also include a hand grip or roof handhold 23. As shown in FIGURE 3, the roof handhold may be directly secured to the frame structure. Since the ladder does not extend beyond the moving frame to cause injury to the user between it and the lading, the guard plate 19 is not extended. However, the roof handle 23 can be secured to the top of the ladder and the guard 19 may be extended upwardly from that shown in the drawings.

From the preceding description, it will be apparent that the ladder need not only be used by railway cars, but may also be used by any other conveyance, such as fire trucks. The ladder may also be used independently as a safety ladder to protect the user of the ladder against any hazards such as fire or exploding objects that may eject from a building against which the ladder is placed.

It will also be apparent from the description that various modifications may be made without departing from the scope of the invention as defined by the following claims.

What is claimed is:

1. A railway car comprising in combination, an underframe, a safety ladder extending upwardly above said underframe and fixed relative to said underframe, a shifting frame structure supported on the underframe for longitudinal movement relative to said underframe and ladder, and means connecting said ladder to said shifting frame structure for relative movement therebetween.

2. A railway car having an underframe and a shifting

frame structure supported on the underframe for longitudinal movement relative to the underframe, the car comprising, a safety ladder extending upwardly above and fixed relative to the underframe, a bracket rigidly supported on the shifting frame structure adjacent to the upper portion of said ladder and a rider integral to said ladder and slidable within said bracket to permit longitudinal movement of said shifting frame structure relative to said ladder.

3. In a railway car having an underframe with couplers mounted at each end of the underframe and a sliding frame structure carried by and cushioned on the underframe for relative longitudinal movement therebetween upon coupler impact, the combination of, a safety ladder immovably fixed on the underframe, said ladder including vertically spaced rungs, a guard plate secured to said ladder in inwardly spaced relation to said rungs and interposed between said ladder and the sliding frame structure to thereby prevent injury to the user of said ladder due to movement of said sliding frame relative to said ladder occasioned by the coupler impact, and means slidably connecting said ladder and the sliding frame structure.

4. A railway car having an underframe and a sliding frame structure supported for longitudinal movement along the underframe, the car comprising, a safety ladder extending upwardly above and fixed relative to the underframe, a U-shaped bracket rigidly supported on the sliding frame structure in spaced relation to the underframe and adjacent to the upper portion of said ladder, a channel-shaped rider integral to said ladder and slidable within said U-shaped bracket to permit longitudinal movement of the sliding frame structure relative to said ladder when the frame structure moves along the underframe, and a guard plate secured to said ladder and interposed between said ladder and the sliding frame structure to thereby prevent injury to the user of said ladder occasioned by the movement of the sliding frame relative to said ladder.

5. In a railway car the combination of, an underframe, means supported on the underframe for longitudinal movement relative thereto, a safety ladder extending upwardly from said underframe alongside said means, said ladder comprising a pair of angled members, each member secured at one end to said underframe, a plurality of

horizontal treads spaced along the upwardly extending length of said angled members and secured thereto, a guard plate interposed between said treads and said means and extending substantially the length of said angled members, said guard plate having perpendicular sides extending towards and secured to said angled members to thereby space said treads from said guard plate, whereby the user of said ladder may hold the treads and insert his feet within the ladder to ascend and descend the ladder while said guard plate protects him from extending his hands and feet into the path of said means during movement thereof relative to the underframe and ladder.

6. A safety ladder comprising a pair of parallel spaced angle sectioned members, each member having one angled leg in the same plane with one angled leg of the other member and each member having its other angled leg extending from the first angled leg in the same direction and in parallel spaced relationship with the other angled leg of the other member, a plurality of treads spaced along the length of said members and secured to the angled legs that are located within the same plane, and a guard plate having perpendicular extending sides extending towards and secured to the parallel angled legs of said members to thereby space said treads from said guard plate and operable to permit partial extension of the hands and feet of the user of the ladder up to the guard plate to enable the user to ascend and descend the ladder while preventing said user from extending his hands and feet beyond said guard plate.

7. In a railway car the combination of, an underframe, means supported on said underframe for longitudinal sliding movement relative thereto, a ladder secured at its lower end to said underframe and extending upwardly alongside said means, bracket means slidably mounting upper portions of said ladder on said means, and plate means interposed between said ladder and said means to prevent contact of a ladder occupant with said means.
